UNITED STATES PATENT OFFICE.

MORRIS A. SCHWARTZ, OF LOS ANGELES, CALIFORNIA.

MAGNETIC DISTORTION MOTOR.

Application filed July 2, 1920. Serial No. 393,623.

To all whom it may concern:

Be it known that I, MORRIS A. SCHWARTZ, a citizen of the United States, residing at Los Angeles, in the county of Los Angeles 5 and State of California, have invented new and useful Improvements in Magnetic Distortion Motors, of which the following is a specification.

This invention is a magnetic distortion 10 motor and has for its object the provision of means for causing rotation of a motor armature by the torque produced by variations in the susceptibility and permeability of the armature with relation to a fixed magnetic field.

It is a further object of the invention to provide a construction of this character in which the variations in the susceptibility and permeability of the armature with relation 20 to its magnetic field are provided by varying the temperature of the armature.

The invention will be readily understood from the following description of the accompanying drawings, in which—

25 Figure 1 is a top plan view, partly broken away, of a motor constructed in accordance with the invention.

Fig. 2 is a side elevation of the motor.

Fig. 3 is a vertical section on the line 3—3 30 of Fig. 1.

Fig. 4 is a plan view of the means employed for varying the temperature of the motor armature.

35 Fig. 5 is a somewhat diagrammatic illustration of a portion of the motor.

Fig. 6 is a similar view showing the parts after a variation in the temperature of the armature.

In the particular embodiment of the invention as illustrated in the drawings, I 40 show a construction consisting of a base 1 having the rotatable shaft 2 extending upwardly therefrom. A disc 3 surrounds shaft 2 and is spaced beyond base 1 as by means 45 of the supporting arms 4. An armature is fixed upon shaft 2 above disc 3, said armature being shown as comprising non-magnetic sections 6 forming supporting means for spaced radially extending plates 7 of 50 magnetic or paramagnetic metal.

A fixed magnetic field is provided for the armature between base 1 and disc 3, said field being shown as comprising pairs of radially spaced pole pieces 9 and 10. The 55 pairs of pole pieces are suitably circumferen-

tially spaced with relation to the armature as clearly shown in Fig. 1, and each of the pole pieces, preferably, consist of a winding 11 received about a core 12 extending upwardly to a point just beneath the armature. 60 The lower ends of the cores of a pair of pole pieces 9 and 10 are, preferably, connected by an arm 13 mounted upon base 1. While I have shown pole pieces constructed as above set forth it will be obvious that any other 65 type of pole pieces, such for example as usual permanent horseshoe magnets may be employed instead of the pole pieces 9—10.

Above each of the pairs of pole pieces 9—10 the disc 3 is cut away as shown at 15 70 so as to expose the pairs of pole pieces, for an appreciable space at each side of said pairs of pole pieces, to the armature arranged above the disc 3. Jets 16 are arranged beneath the armature so as to discharge 75 against the same, one of said jets being arranged at each of the openings 15 in such manner as to be shifted circumferentially relative to the armature from one side to the other of the pair of pole pieces at said opening. As an instance of this arrangement the jets may extend upwardly from an annular pipe 17 arranged to extend through the spaces between the pole pieces of the respective pairs. This annular pipe may be 80 supported by a spider 18 having a collar 19 rotatably mounted upon shaft 2 and supported by collar 20 fixed upon said shaft. The pipe 17 is connected by a suitable flexible connection 21 to a source of supply for a 85 heat or cold creating element. This heat or cold creating element is adapted to be discharged through jets 16 against the armature, and the spider supporting pipe 17 and the jets is arranged to be circumferentially 90 shifted so as to position the jets at one side or the other of the radial line connecting the pole pieces of each of the fixed magnets. 95

The operation of the device will be readily understood by reference to Figs. 5 and 6. 100 The jets 16 being at one side or the other of the pole pieces of the fixed magnets, and discharging an element against the armature which is adapted to either raise or lower the temperature of the metallic strips of said 105 armature, will change the susceptibility and permeability of the metallic strips at that side of the radii connecting the pole pieces of the fixed magnets with relation to the fixed magnets, so that the normal uniform 110

magnetic field between the pole pieces, and as shown in dotted lines in Fig. 5, will be distorted as shown in dotted lines in Fig. 6. This distortion of the magnetic field will 5 cause a greater attraction between the armature and the magnetic field at one side of the radii connecting the pole pieces of the magnets than at the other side thereof, and as a result the armature will be rotated in response to said increase of magnetic force.

When it is desired to reverse the direction of rotation of the armature it is only necessary to shift jets 16 from one side to the other of the radii connecting the pole pieces 15 of the magnets. Power may be taken from shaft 2 rotated by the armature in any suitable manner shown as including a pulley 24 fixed upon said shaft.

Various changes may be made without departing from the spirit of the invention as 20 claimed.

What is claimed is:

1. A motor comprising an armature having radially disposed temperature varying 25 magnetic elements, field magnets and heating jets disposed around and below said armature, said field magnets having two poles, and the heating jets being adapted to be passed between said poles.

2. A motor comprising an armature having temperature varying magnetic elements, field magnets, and heating jets movable between the magnets to occupy two extreme positions in which said elements act upon the magnets to effect movement of the armature in one direction or the other according as the jets occupy one extreme position or the other.

3. A motor comprising two annular series of field magnets arranged concentric to each other, an armature at one side of the magnets formed of temperature varying magnetic elements spaced by non-magnetic elements, a stationary member interposed between the magnets and said armature and having slots formed therein to expose the cores of said magnets, and heating jets interposed between the two series of magnets and arranged at intervals to correspond with said slots, said jets being movably sustained to occupy one extreme position in which they are disposed at one side of the cores of said magnets, and in another extreme position in which they are disposed at the other side of said cores.

In testimony whereof I have signed my name to this specification.

MORRIS A. SCHWARTZ.
